Patented Sept. 21, 1965

202,331

PET ANIMAL MASTICATION AID

Stanton E. Fisher, University City, Mo.
(1347 Maryland Ave., St. Louis 30, Mo.)

Filed Jan. 2, 1964, Ser. No. 78,004

Term of patent 14 years

(Cl. D12—2)

Fig. 1

Fig. 2.

Fig. 3.

FIGURE 1 is a top plan view of a pet animal mastication aid.

FIGURE 2 is a left side elevational view thereof.

FIGURE 3 is a right side elevational view thereof.

The rear is a mirror image of the front except that the facial-like features are omitted.

I claim:

The ornamental design for a pet animal mastication aid, as shown and described.
